UNITED STATES PATENT OFFICE.

EDWIN SPEAR ACHESON, OF RICHMOND HEIGHTS, MISSOURI.

LIQUID RHEOSTAT.

Application filed April 26, 1926. Serial No. 104,802.

My present invention has reference to a lighting device for gas ranges or the like, and my object is the provision of an electric lighter for this purpose in which an electrolytic cell or transformer is employed having one of its electrodes wired to the house supply, the second electrode being wired to a fuse and from thence to a lighting electrode, the latter when brought into contact with the burner will create a spark to light the gas when the gas cock is turned on.

To the attainment of the above broadly stated objects and others which will appear as the nature of the invention is better understood, the improvement resides in certain features of construction, combination and operative association of parts, a satisfactory embodiment of which is illustrated by the accompanying drawings.

20 In the drawings:

Figure 1 is an elevation illustrating the application of my improvement.

Figure 2 is a longitudinal sectional view through the box containing the electrolytic cell or rectifier.

Figure 3 is an elevation of the lighting electrode, the handle portion thereof being in section.

Figure 4 is a sectional view through the electrolytic jar or rectifier.

Figure 5 is a view to illustrate the circuit.

Referring now to the drawings in detail, the numeral 1 designates the upper portion of an ordinary gas range and 2 one of the burners therefor. Before proceeding with the description of my improvement it may be well to state that I do not desire my invention restricted as a lighting means for gas ranges, as the same may be employed 40 with equal efficiency for lighting other devices.

Supported on a bracket 3, at a suitable distance above the range 1 there is a box 4. The top of the box is normally closed by a hinged cover 5, the said cover being provided with a handle 6 whereby, when the cover is latched on the box and detached from the bracket 3, the said box may be conveniently carried from place to place.

50 In the box 4 there is a glass jar 7. The jar has screwed on the mouth thereof the usual cap 8. Centrally secured to the cap by means 9, there is a fibre block 10. Along one side or edge of the fibre block there is a paper strip 11. Connected by means 12 to the paper strip and to the block 10 there is

a copper strip 13 that provides one of the electrodes. Connected to the opposite side or edge of the strip by means 14, there is the second electrode 15. This electrode is 60 spaced from the block 10 by mica or other insulated washers 16. By reference to Figure 4 of the drawings it will be noted that the electrode 15, from its lower connecting element 14, is extended at an outward angle, 65 as indicated by the numeral 17, and from thence is arranged in a plane with its upper straight or connected portion, as indicated by the numeral 18. Both of the electrodes project a suitable distance below the fibre 70 block 10, and the end 18 of the electrode 15 may be bent a desired distance away from the end of the electrode 13. The electrolyte in the jar is indicated by the numeral 19. The jar is partly filled with water with 75 which is mixed an electrosalts. The level of the electrolysis is indicated by the numeral 19', in Figure 4 of the drawings.

The upper connecting element for the electrode 13 serves as a binding post for a cable 80 20 that is connected to a plug 21 that enters a wall socket.

The upper connecting element 14 for the electrode 15 serves as a binding post for a second cable 24. In the box there is a fuse 85 25 to which the said cable 24 is attached. From the fuse there is directed a cable 26 that is secured to a binding post 27 on the box 4 and also secured to the binding post there is a cable 28 that is passed through a longitudinal opening arranged concentrically with respect to the axial plane of an insulator handle 29. The cable 28 is secured to one end of a lighting electrode 30 that is screwed in the handle 29. The outer end of the handle has an eye 31 thereon, and this eye is designed to engage with a hook 32 on the box 4, when the lighter is not required for use.

It will be apparent to those skilled in the art to which this invention relates that when the lighting electrode is brought into contact with the burner 2, after the gas has been turned on, an electric circuit will be completed and a spark will be created at the burner to ignite the gas. The device may be safely handled, and the lighter when not in use is, as stated, suspended from the hook 32. The intensity of the spark is regulated by adjusting the copper electrode 15 110 toward or away from the copper electrode 13.

Having described the invention, I claim:—

A rheostat comprising a receptacle containing a liquid and having a threaded neck portion, a flanged cap screwed on said neck portion, for closing the mouth of the receptacle, a fibre block secured to the cap, extending inwardly therefrom and designed to be received in the liquid in the receptacle, paper strips along the edges of the block, metal plates comprising electrodes arranged

against the strips and removably secured to the fibre block, one of said electrodes being secured to the block only at its outer portion, cables guided through the cap and connected to one of the securing means for each of the electrodes, and one of said conductors designed to be connected to an electric circuit.

In testimony whereof I affix my signature.

EDWIN SPEAR ACHESON.
